UNITED STATES PATENT OFFICE.

FRANK WORTH, OF SEATTLE, WASHINGTON.

BOAT-LAUNCHING APPARATUS.

1,315,895.

Specification of Letters Patent.

Patented Sept. 9, 1919.

Application filed January 30, 1919. Serial No. 273,946.

To all whom it may concern:

Be it known that I, FRANK WORTH, a citizen of the United States, residing at Seattle, in the county of King and State of Washington, have invented certain new and useful Improvements in Boat-Launching Apparatus, of which the following is a specification.

The object of this invention is to provide improved apparatus for stowing and launching ships' boats.

The invention consists in a boat-supporting cradle which is tiltably connected at the gunwale of a ship to enable the boat to be stowed in an inverted position above the deck of the ship, or be swung outward into upright position preparatory to lowering into the water.

An important feature of the invention is in the novel means for utilizing boat hoisting and lowering cables or ropes to not only perform such functions, but also for controlling and actuating the movements of the cradle.

The invention furthermore consists in the novel means for detachably connecting the boat to its cradle, and also in means whereby the boat is detachably connected to the aforesaid cables.

The invention is illustrated in the accompanying drawings, wherein—

Figure 1 is a view in transverse vertical section of apparatus embodying my invention applied to a ship, with the cradle in its outboard position, the boat shown in full lines being secured thereto, in dotted lines in a lowering position. Fig. 2 is a transverse vertical sectional view of a portion of the ship, with the apparatus and boat shown in end elevation, the cradle and boat being shown in full lines in tilted positions and by dotted lines in the inboard or stowed positions. Fig. 3 is a fragmentary perspective view of the boat cradle illustrated in an inverted position. Fig. 4 is a plan view with the parts in positions which correspond with the positions in which they are shown by full lines in Fig. 1. Fig. 5 is a detail longitudinal vertical section of portions of the boat to show the releasing appliances therefor.

In carrying out my invention, I provide a cradle comprising a frame F having legs 10 depending from one of its sides and connected by pivotal pins or bolts 11 to stand-

ards 12 which are rigidly secured to a ship at or near the gunwale 13 of the ship's boat deck 14. The legs are of lengths to support the frame approximately parallel to said deck when the frame is in its inboard position, as indicated by dotted lines F^a in Fig. 2. The lower ends of said legs are bifurcated to provide two branches 10¹.

15 represent posts rigidly secured upon said deck to the ship structure. Cables 16 connecting the upper ends of the posts with the frame adjacent to the legs 10 serve to support the frame when in its outboard position (Fig. 1), substantially parallel to the deck.

Provided in the frame F adjacent to its ends are rotary devices 17 having fingers 17¹ adapted to engage under the thwarts as T of a ship's boat B to detachably couple the boat to the frame and below the latter when 75 in its Fig. 1 position.

Secured to the boat B subjacent to each end of the cradle frame are socket attachments 18 to accommodate heavy bodies 19 which are releasably connected to the sockets by latch bolts 20 (Fig. 5) extending through registering holes of the respective members. Said latch bolts are connected by links 21 to a lever 22 fulcrumed at 22¹ to a stand 23 whereby an operator in the boat may withdraw the bolts from said bodies to release the boat when it is lowered by the attached boat-lowering and hoisting falls 24 into proximity to the water surface. The above-mentioned falls 24 lead from the bodies upwardly, as in Fig. 1, over grooved sheaves 25 provided in blocks 25¹ secured to the ends of the cradle frame, thence pass over grooved sheaves 26 provided in the upper ends of the respective posts 15 and are 90 led to winding drums 27. These winding drums, as illustrated, are mounted on shafts 28 arranged to be rotated by means of bevel gears 29 from shafts 30 carrying worm wheels 31 engaging worms 32 provided on a longitudinal shaft 33. The shaft 33 may be driven by any suitable power means or, as shown, through the instrumentality of a manually-actuated crank 34.

Supplementary to the aforesaid boat 105 hoisting and lowering falls 24, I provide a second fall 35 at each end of the frame in proximity to the adjacent leg 10 and extending over a grooved sheave 36 on the respective post 15 to a drum 37 mounted on a 101

longitudinal shaft 37¹. The shaft 37¹ may be rotated by suitable means as, for example, a lever 38 provided with a pawl 38¹ engaging a ratchet wheel 39 secured to the shaft. 5 40 represents a dog engageable with said ratchet wheel to prevent the drum shaft 37¹ turning during the intermittent engagement of the operating pawl.

As shown, the shaft 37¹ is desirably journaled in bracket boxes 41 connected to posts 10 15. The other beforementioned shafts 28, 30 and 33 are shown as journaled in bearing boxes provided in standards 42 secured to the ship's deck 14.

15 The operation of the invention may be explained as follows:

Assuming that the hoisting and lowering falls 24 are connected by the releasable devices comprising sockets 18, bodies 19 and 20 lock bolts 20 to the boat when in the water 25 alongside of the ship, and with the cradle in its outboard position, as shown in Fig. 1, then by suitably turning the shaft 33, the drums 27 are rotated to effect the hoisting of the boat, until the latter is brought into 30 juxtaposition with the underside of the cradle frame F. When thus positioned, the operation of the shaft 33 is discontinued until the boat is secured to the cradle by means of the fingers 17¹ being engaged by a 35 man in the boat beneath the thwarts T. The drums 27 are thereupon actuated to cause the cradle to be swung upwardly and inwardly with respect to the ship, and as the 40 center of gravity of the boat and cradle swings beyond a plane extending vertically through the pivotal pins 11, the falls 24 engage in the crotches between the branches 10¹ of the respective legs 10 to accordingly support the cradle in the lowering of the 45 cradle and boat from their full-line positions to their dotted line positions, as indicated in Fig. 2.

To launch the boat, the cable is wound 50 upon the drums 27 to exercise a lift through each of the legs 10 to elevate the cradle until the centers of gravity of the weights of the boat and cradle have passed beyond the vertical plane through the cradle's pivotal connections, whereupon the falls 35 are paid out to lower the cradle and boat into 55 their outboard positions, Fig. 1. The boat is then detached from the cradle by manipulating the devices 17, whereupon the boat is lowered by means of the falls 24 until within a short distance from the water, when the boat is released by the coxswain through the medium of the lever 22.

60 From the foregoing it is evident that a boat may be brought from its inverted stowed position on the ship into lowering position by swinging the cradle through the agency of the falls 24 and after being disconnected from the cradle, the boat may be 65 lowered by the falls 24.

These operations can be performed in a most rapid manner while the ship is moving, or otherwise.

What I claim, is—

1. In apparatus of the class described, the 70 combination with a ship, of two posts secured upon a deck thereof, sheaves provided on said posts, a cradle, means to tiltably connect said cradle to the ship; a boat supported by said cradle, and cables passing over 75 said sheaves and adapted to be releasably connected to the boat for effecting the tilting of said cradle and the subsequent lowering of the boat therefrom.

2. In apparatus of the class described, a 80 ship's boat, a tiltable cradle therefor, posts, sheaves provided on said posts, cables passing over said sheaves and detachably connected to the boat, means to actuate said cables for effecting the tilting of said cradle, 85 devices for retaining the boat on the cradle during the tilting movements of the latter, and means connected with the cradle for tilting the same independently of the aforesaid cables. 90

3. In apparatus of the class described, the combination with a ship and a ship's boat, of posts provided on the deck of said ship, sheaves mounted on the respective posts, a cradle for said boat, said cradle being 95 hingedly connected with the ship to enable the cradle to be swung into inboard and outboard positions with respect to the ship, and cables passing over said sheaves for raising and lowering the boat to and from the cradle 100 when the latter is in its outboard position, said cables also serving to swing the cradle and boat from their outboard to inboard positions and vice versa.

4. In apparatus of the class described, the 105 combination with a ship, of standards secured thereto, a boat cradle tiltably connected from one of its sides to said standards and having legs supporting its other side, a boat, posts provided on the ship, sheaves 110 provided on said posts, drums, cables releasably connected to the boat and passing over said sheaves to the respective drums, and means to operate said drums to effect the tilting of the cradle through the medium of 115 said cables.

5. In apparatus of the class described, the combination with a ship, of standards secured thereto, a boat cradle tiltably connected from one of its sides to said standards and having legs supporting its other side, a boat, means for detachably connecting said boat to the cradle, posts provided on the ship, sheaves provided on said posts, drums, cables releasably connected to the 125 boat and passing over said sheaves to the respective drums, and means to operate said drums to effect the tilting of the cradle through the medium of said cables acting in 130 coöperation with the cradle legs.

6. In apparatus of the class described, a
tiltable cradle comprising a frame having
legs supporting one side of the frame, stand-
ards hingedly connected to said frame to
5 support the latter from its opposite side, and
cables coöperating with said legs to effect
the tilting of the cradle.

Signed at Seattle, Washington, this 24th
day of January, 1919.

FRANK WORTH.
